Charles S. Gooding.

UNITED STATES PATENT OFFICE.

JACOB L. SHROYER, OF PITTSFIELD, MASSACHUSETTS.

TIRE-PUMPING MECHANISM.

1,276,126.

Specification of Letters Patent. Patented Aug. 20, 1918.

Application filed April 30, 1917. Serial No. 165,436.

To all whom it may concern:

Be it known that I, JACOB L. SHROYER, a citizen of the United States, residing at Pittsfield, in the county of Berkshire and 5 State of Massachusetts, have invented new and useful Improvements in Tire-Pumping Mechanism, of which the following is a specification.

This invention relates to a mechanism for 10 inflating pneumatic tires, the object of the invention being to utilize one of the cylinders and pistons of a gas engine to pump up the tire of an automobile, and to utilize the same in such a manner that no gases will 15 pass from the cylinder through the air tube into the pneumatic tire.

The invention consists in the combination and arrangement of parts set forth in the following specification and particularly 20 pointed out in the claims thereof.

Referring to the drawings:

Figure 1 is a sectional elevation of one form of internal gas combustion engine, embodying my invention.

25 Fig. 2 is a sectional elevation of the air inlet valve and its air conducting means.

Fig. 3 is a sectional elevation of the specific means whereby the connections from the gas inlet valve and exhaust valve to the 30 cams are thrown into and out of operation.

Fig. 4 is a sectional elevation taken on line 4-4 of Fig. 3.

Fig. 5 is a sectional elevation similar to Fig. 2 illustrating a modified form of my 35 invention.

Like numerals refer to like parts throughout the several views of the drawings.

In the drawings, referring to Figs. 1 to 4 inclusive, 6 is one of the cylinders of a 40 series of cylinders in a gas combustion engine, 7 is the piston of said cylinder, 8 the connecting rod, 9 the crank-shaft, 10 is the gas inlet valve, 11 the exhaust valve, 12 and 13 the cam shafts and 14 and 15 the cams.

45 The inlet valve 10 is connected to the cam 14 by two rods 16 and 17 which are connected together by a sleeve 18. A roll 17' is rotatably mounted in the lower end of the rod 17 and engages the cam 14. The rod 50 16 has screw-threaded connection with the sleeve 18, the rod 17 has sliding engagement with the interior of the sleeve 18 and when the parts are in operative position the upper end of the rod 17 bears against 55 the lower edge of a plate 19 which is pro-

vided with a stem 20 extending through the sleeve 18 and having a handle 21 thereon.

A cross-pin 22 is fast to the stem 20 and is adapted to project into a slot 23 in the sleeve 18, being forced into said slot by a spring 60 24 which encircles the stem 20 and bears at one end against the handle 21 and at the other end against said sleeve. When desired, the stem 20 can be rotated by means of the handle 21 until the plate 19 assumes 65 a position at right angles to that shown in Figs. 3 and 4, and when the handle 21 is released the spring 24 will force the cross-pin 22 into another notch 25 in the sleeve 18.

A spring 26 encircles the rod 16 and bears 70 at its lower end against a collar 27 on said rod and at its upper end against a collar 28 on a stationary sleeve 29.

It will be seen that when the parts are in the positions shown in Figs. 3 and 4, the 75 connecting rods 16 and 17 and the sleeve 18 will act as one piece, so that the cam 14 will raise the gas inlet valve 10 from its seat and the spring 26 will return it to its seat in proper time. If, however, the plate 19 is 80 turned at right angles to the position shown in Figs. 3 and 4, then the rod 17 will play up and down in the sleeve 18 and the valve 10 will be held closed at all times by the spring 26.

85 The connections from the cam 15 to the exhaust valve 11 are substantially the same as the connections just described which extend from the cam 14 to the inlet valve 10 and, therefore, a description of one will 90 apply equally well to the other.

A plug 30 is screwed into the cylinder head 31 and has an air inlet passage 32 therein which opens from the atmosphere and terminates at its lower end in a port 95 33. A valve 34 bears against a seat 35 on said plug and is adapted to open or close said inlet port 33. The valve 34 is provided with a tubular valve stem 36 which is screw-threaded to receive a nut 37.

100 A light spring 38 encircles the valve stem 36 and bears at its upper end against the nut 37 and at its lower end against the plug 30, thus tending to hold the valve 34 upon its seat. Inside the spring 38 is a heavier 105 spring 39 which, under normal conditions, bears at its lower end upon the plug 30, but its upper end falls short of bearing against the nut 37. The object of this inner spring is to hold the valve 34 closed under all con- 110

ditions when the screw 37 is screwed down upon the valve stem 36 until it abuts against the upper end of said heavy spring 39.

A petcock 40 is attached to the upper end 5 of the screw-threaded valve stem 36, said petcock having a tubular extension 41 in which is located a check valve 42. An air conducting pipe 43 is fastened at one end thereof to the tubular extension 41 and at 10 its other end is connected to the air valve of a pneumatic tire in a manner well known to those skilled in this art.

The general operation of the device hereinbefore described and illustrated in Figs. 15 1 and 4 inclusive is as follows: When it is not desired to use the device for the purpose of inflating a tire the usual parts of the gas engine operate in their ordinary well known manner. When, however, it is desired 20 to use one of the pistons of the gas engine and its cylinder for the purpose of pumping air into a pneumatic tire, the petcock 40 is opened and the connecting rods 16 and 17 are disconnected from operative 25 relation to each other by turning the stem or pin 20 until the plate 19 is moved from the position illustrated in Figs. 3 and 4 to a position at right angles thereto. The cams 14 and 15 will then operate only to slide the 30 rod 17 up and down in the sleeve 18, but the rod 16 will be left stationary and, therefore, the inlet valve 10 and exhaust valve 11 will remain stationary and closed.

It will be understood that the crank-shaft 35 9 is rotated by the pistons in the other cylinders which are operated in the usual manner and as the crank-shaft 9 rotates the connecting rod 8 will cause the piston 7 to play upwardly and downwardly in the cylinder 40 6 and as it moves downwardly it will cause the valve 34 to be opened and let air enter through the passage 32 and inlet port 33 into the cylinder 6. Upon the return stroke 45 of the piston the valve 34 will become closed and air will pass through the tubular stem 36 and petcock 40, opening the check valve 42 and passing into the air conducting tube 43, thence through the air valve of the pneumatic tire and into said pneumatic tire. When the tire has been inflated 50 sufficiently the air tube is removed from the extension 41 and from the air valve of the pneumatic tire and the petcock 40 is closed while the valve 34 is prevented from opening 55 during the subsequent normal action of the engine piston 7 and inlet valve 10 and exhaust valve 11 by screwing the screw 37 downwardly upon the valve 36 until it engages the heavy spring 39, whereupon the 60 strength of the two springs 38 and 39 is such that the valve 34 cannot be opened by downward movement of the piston 7 to admit air from the atmosphere.

In Fig. 5 I have illustrated a modified 65 form of my invention in which the same is

shown as adapted to be used in connection with a priming cock of a gas engine. Referring to Fig. 5, 44 is a plug in the cylinder head 45. 46 is a priming cock to which is connected the air conducting tube 47 which extends from the priming cock 46 to the air valve of a pneumatic tire. The air passes into the cylinder through an air inlet passage 48 which terminates at its lower end in a port 49, said port being closed by a valve 50 which is held against a seat 51 by a spring 52 which encircles the valve stem 53 and bears at its upper end against an adjusting screw 54 which has screw-threaded engagement with the valve stem 53.

When this form of my invention is in operation the gas inlet and exhaust valves are disconnected from the cam shafts, as hereinbefore described in relation to the form of my invention illustrated in Fig. 1, and the priming cock 46 is opened to allow air to pass from the cylinder through the priming cock and into the air conducting tube 47. On the downward movement of the piston in the cylinder, its gas inlet and exhaust valves being thrown out of operation as hereinbefore described, air passes into the cylinder through the inlet passage 48, the valve 50 opening to allow said air to pass into the cylinder. Upon the return movement of the piston the air passes through the priming cock 46 into the air conducting tube 47 and thence through the air valve of the pneumatic tire and into said pneumatic tire. The tire thus becomes inflated and as soon as it has been sufficiently inflated the priming cock 46 is closed and the connections to the valves 10 and 11 are made operative in the manner hereinbefore described and the engine is then in condition to be used in the usual manner, with all of its cylinders in operation to rotate the crank-shaft.

Having thus described my invention, what I claim and desire by Letters Patent to secure is:

1. A tire pumping mechanism having, in combination, an organized gas engine comprising a cylinder, a cylinder piston, means to impart a reciprocatory motion to said piston, said cylinder having an air inlet port opening thereinto, a valve adapted to open and close said port, a hollow stem fast to said valve and terminating at one end thereof in a port opening out of said cylinder, a spring encircling said valve stem and adapted to hold said valve normally closed and air conducting means adapted to connect said stem to the air valve of a pneumatic tire.

2. A tire pumping mechanism having, in combination, an organized gas engine comprising a cylinder, a cylinder piston, means to impart a reciprocatory motion to said piston, said cylinder having an air inlet port

opening thereinto, a valve adapted to open and close said port, a hollow stem fast to said valve and terminating at one end thereof in a port opening out of said cylinder, a spring encircling said valve stem, a nut having screw-threaded engagement with said valve stem, said spring bearing at one end against said nut and at the other end against a stationary member and air conducting means adapted to connect said valve stem to the air valve of a pneumatic tire.

3. A tire pumping mechanism having, in combination, an organized gas engine comprising a cylinder, a cylinder piston, means to impart a reciprocatory motion to said piston, said cylinder having an air inlet port opening thereinto, a valve adapted to open and close said port, a hollow stem fast to said valve and terminating at one end thereof in a port opening out of said cylinder, a light spring encircling said valve stem, a nut having screw-threaded engagement with said valve stem, said spring bearing at one end against said nut and at the other end against a stationary member, a comparatively heavy spring also encircling said valve stem and shorter than said first-named spring and air conducting means adapted to connect said valve stem to the air valve of a pneumatic tire.

4. A tire pumping mechanism having, in combination, an organized gas engine comprising a cylinder, a cylinder piston, means to impart a reciprocatory motion to said piston, a gas inlet valve, a gas outlet valve, a cam shaft and cams and connections from said cams to said gas inlet and gas exhaust valves, each of said connections comprising a valve stem, a sleeve having screw-threaded engagement with said valve stem, a rod having sliding engagement with said sleeve and a plate rotatably mounted on said sleeve and projecting between adjacent ends of said stem and rod, whereby said connections may be thrown out of operation and whereby said gas inlet valve and gas outlet valve will remain closed during the operation of said cylinder piston, said cylinder having an air

inlet port opening thereinto, a spring actuated valve adapted to open and close said port, said cylinder having an air outlet port opening out of the same, and air conducting means adapted to connect said air outlet port to the air valve of a pneumatic tire.

5. A tire pumping mechanism having, in combination, an organized gas engine comprising a cylinder, a cylinder piston, means to impart a reciprocatory motion to said piston, said cylinder having an air inlet port opening thereinto, a valve adapted to open and close said port, a hollow stem fast to said valve and terminating at one end thereof in a port opening out of said cylinder, a spring encircling said valve stem and adapted to hold the same normally closed, a manually operable petcock fast to the upper end of said valve stem, and air conducting means adapted to connect said petcock to the air valve of a pneumatic tire.

6. A tire pumping mechanism having, in combination, an organized gas engine comprising a cylinder, a cylinder piston, means to impart a reciprocatory motion to said piston, said cylinder having an air inlet port opening thereinto, a valve adapted to open and close said port, a hollow stem fast to said valve and terminating at one end thereof in a port opening out of said cylinder, a spring encircling said valve stem and adapted to hold the same normally closed, a manually operable petcock fast to the upper end of said valve stem, air conducting means adapted to connect said petcock to the air valve of a pneumatic tire and a check valve interposed between said air outlet port and said air conducting means to prevent air entering said cylinder through said outlet port.

In testimony whereof I have hereunto set my hand in presence of two subscribing witnesses.

JACOB L. SHROYER.
